UNITED STATES PATENT OFFICE.

WALTON G. WILCOX, OF CLOVERLY, WYOMING.

SEALING DEVICE FOR AIR-TIGHT VESSELS.

No. 892,344.

Specification of Letters Patent. Patented June 30, 1908.

Application filed August 22, 1907. Serial No. 388,751.

To all whom it may concern:

Be it known that I, WALTON G. WILCOX, citizen of the United States, residing at Cloverly, in the county of Bighorn and State of Wyoming, have invented certain new and useful Improvements in Sealing Devices for Air-Tight Vessels, of which the following is a specification.

This invention relates to can closures, and 10 has special reference to a device adapted to be soldered to a can-cover and over a discharge hole or vent in said cover, and adapted to be torn from over such vent without being detached entirely from said cover.

15 The object of the invention is to provide a novel and peculiar device adapted to be soldered or otherwise fixed to a can-cover for closing or sealing a discharge hole in the cover, and adapted to form a pouring-spout 20 and a hanger for an opening key, in sealed or unsealed position.

A further object of the invention is to provide a novel and peculiar key for operating the sealing device, and adapted to be employed as a stopper for a pouring-hole or vent 25 in the can-cover.

In the accompanying drawings forming part of this application:—Figure 1 is a top view of a can showing the application of the 30 invention. Fig. 2 is a sectional view of a can-cover showing (in dotted lines) the key applied as a stopper, and the sealing device as a pouring-spout, the key-hanger or hook bent in position. Fig. 3 is a plan view 35 of the sealing device. Fig. 4 is a perspective view of the device as shown in Fig. 2. Fig. 5 is a perspective view of the key.

The same reference numerals denote the same parts throughout the several views of 40 the drawings.

The cover 1, of the can 2, has a raised portion 3, flush with the edge of the cover so as to be elevated slightly above the central surface of the cover, for the purpose hereinafter 45 described. Said portion 3 has a discharge-vent or hole 4, and a groove 5 leading from near said vent to the edge of the said portion toward the center of the can-cover. The said groove forms a guide for one prong of an 50 opening key 6.

The sealing device is composed of thin sheet or flexible metal and comprises a plate 7, having a lip 8, which projects from the raised portion 3, when the plate is soldered over the vent 4; two slits 9 partly separate 55 the plate from a pair of ears 10, to permit the sides of the plate to be bent away from the ears, after the plate is bent into position perpendicular to the can-cover, to form a pouring-spout 11. The ears are permanently soldered or otherwise fixed to the top of the can-cover, and the ears have a tongue 12 projecting centrally therefrom. The part of the tongue nearest the ears is attached to the rim of the cover 1, so as to leave a free 60 end adapted to be bent into a key-hanger or hook 13.

The key 6 is conical and has a slot 14, dividing the key lengthwise into a short prong 15, and a long prong 16; the said slot being 70 of such length as to receive the lip 8, with the long prong reaching over on the plate 7, while the short prong, which has a beveled end, is worked under the said lip against the joint. There is sufficient soldered conical 75 portion of the key between the said slot and the handle 17, of the key to form a stopper for the vent when the latter is unsealed. Said handle is at an angle to the key body so as to permit its being grasped for operating the key vertically over the top of the can-cover, by reason of the elevation of the portion 3, to break or tear the plate 7, from over the vent 4. The key handle has an elongation 18, by which the key may be 80 hung from the hanger or hook 13.

Having thus described my invention what I claim as new and desire to secure by Letters Patent is:—

1. A device for closing and opening vents 90 of air-tight cans, comprising a plate of flexible metal adapted to form a closure and a pouring-spout, a pair of securing ears, a tongue projecting from the plate between the ears and forming a hook, and adapted 95 to support a suitable key for operating the plate.

2. The combination with an air-tight vessel having a vent, of a sealer or closure for the vent composed of flexible metal and com- 100

prising a plate soldered over the vent, and having an inwardly projecting free lip, a pair of ears partly separated from the plate and fixed to the vessel adjacent said vent, and a tongue having a portion fixed to the vessel and a portion adapted to form a hook, said plate adapted to form a pouring spout.

In testimony whereof I affix my signature in presence of two witnesses.

WALTON G. WILCOX.
